UNITED STATES PATENT OFFICE.

MALCOLM MACLEOD, OF TORONTO, ONTARIO, CANADA.

HEATING SHIPS AND THE LIKE.

1,114,498.

Specification of Letters Patent. Patented Oct. 20, 1914.

Original application filed November 1, 1913, Serial No. 798,769. Divided and this application filed February 24, 1914. Serial No. 820,713.

To all whom it may concern:

Be it known that I, MALCOLM MACLEOD, a subject of the King of Great Britain, and resident of Toronto, in the Province of Ontario, Dominion of Canada, have invented 5 certain new and useful Improvements in the Heating of Ships and the like, of which the following is the specification.

This invention relates to the heating of 10 ships and other types of maritime vessels, and the object of the invention is to prevent the formation of ice on the hull of a ship, and it consists essentially of providing a 15 heated zone located partially below the water line of the said ship and extending upwardly and across the deck thereof, the parts being arranged and constructed in detail as hereinafter more particularly described in the following specification and accompanying 20 drawing forming part of the same.

In the drawings, Figure 1 is a perspective view of part of the hull of a ship, the side and deck plates being partly broken away to show the ribs of the ship. Fig. 2 is a 25 sectional plan view of part of the hull of a ship. Fig. 3 is a sectional elevation of one 30 of the heating compartments. Fig. 4 is a cross sectional detail of the ribs connecting the inner casing and the outer hull of the ship.

Like letters of reference refer to like parts in the several drawings.

It may be stated that the particular manner in which the heat is applied to the ship 35 is the same as that adapted to heat lock gates and the like described in my application, Serial Number 798,769, filed November 1, 1913, from which the present application has been divided.

Referring to the drawings, A represents 40 part of the body of a ship which is preferably constructed of an outer hull B and an inner casing C. The inner casing C is located partly below the water line and extends upwardly and across the deck, the 45 said casing being rigidly secured to the ribs of the ship and to the outer hull by rivets and the like.

The ribs 1 may be of any usual construction 50 such as angle members carrying web plates attached thereto. In the embodiment illustrated Z shaped sections are shown which can be utilized in ships of small capacity.

The space D provided between the outer 55 hull B and the inner casing C is sub-divided

into compartments 3 by means of the ribs 1, such compartments running transversely around the ship. Should it be found desirable the compartment 3 can be further subdivided by longitudinal members, and arranged in groups in which the adjacent compartments communicate with each other through the conduits or orifices 4, such orifices extending through the top and the bottom of consecutive ribs, the said groups of compartments being separated by the solid rib 6 located therebetween.

7 represents inlet pipes communicating with the compartments 3 through the orifices 8, such pipes being designed to deliver steam, hot air, flue gases and the like to the said compartments. These hot gases circulate through the several compartments 3, the ribs of the ship located between the compartments acting as baffle plates, the said gases being discharged through the outlet pipe 9 to a suitable receiver where they can be reheated, or from which they are finally discharged.

The inlet pipes 7 are of any suitable form and steam or the like is delivered into every alternate compartment, the outlet pipe 9 being connected to the compartment located between those with which the inlet pipe communicates. The object of this will be clearly seen as circulation in each compartment must take place before the gases are discharged therefrom. When steam is utilized as the heating element the water of condensation is returned to the hot well from which it is fed to the boiler.

In heating small vessels since it is not desirable to weaken the ribs of the vessel by having orifices therethrough, an alternate 95 method of forming communication between the several compartments is shown in Fig. 3 and Fig. 4 where a groove 10 is cut in the inner casing between any two adjacent compartments.

Although the compartments 3 are primarily meant to form a heating zone around the casing, they may also be utilized as flotation tanks and the flow of hot gases to and from the said compartments can be cut off by a 105 suitable valve arrangement as found desirable.

As many changes could be made in the above construction and many apparently widely different embodiments of my invention, within the scope of the claims, constructed without departing from the spirit 110.

or scope thereof, it is intended that all matter contained in the accompanying specification and drawings shall be interpreted as illustrative and not in a limiting sense.

5. What I claim as my invention is:

1. The combination with the outer hull of a ship, of an inner casing located partly below the water line and extending upwardly and across the deck, means of subdividing 10 the said casing into compartments, and means of supplying heat to the said compartments, as and for the purpose specified.

2. The combination with the outer hull of a ship, of an inner casing located partly below the water line and extending upwardly 15 and across the deck, ribs located between the outer hull and inner casing and adapted to subdivide said casing into compartments, such ribs having orifices therethrough, and 20 means of supplying heat to the said compartments, as and for the purpose specified.

3. The combination with the outer hull of a ship, of an inner casing located partially below the water line and extending upwardly and across the deck, ribs located between the 25 outer hull and the inner casing and adapted to subdivide the said casing into compartments, such ribs having orifices therethrough, an inlet pipe connected to such compartments through which steam and the 30 like are designed to pass and an outlet pipe connected to the said compartment and through which the steam and the like is designed to be discharged, as and for the purpose specified.

35 In witness whereof I have hereunto set my hand in the presence of two witnesses.

MALCOLM MACLEOD
